UNITED STATES PATENT OFFICE.

HENRY W. MERRITT, OF SPRINGFIELD, MASSACHUSETTS, AND WALTER J. BARRON, OF BROOKLYN, NEW YORK, ASSIGNEES TO DENSMORE TYPEWRITER COMPANY, OF SYRACUSE, NEW YORK, A CORPORATION OF NEW YORK.

TYPE-WRITING MACHINE.

SPECIFICATION forming part of Letters Patent No. 774,262, dated November 8, 1904.

Original application filed February 6, 1902, Serial No. 92,839. Divided and this application filed July 26, 1902. Serial No. 117,065.
(No model.)

To all whom it may concern:

Be it known that we, HENRY W. MERRITT, a resident of Springfield, county of Hampden, and State of Massachusetts, and WALTER J. BARRON, a resident of the borough of Brooklyn, county of Kings, city and State of New York, citizens of the United States, have invented certain new and useful Improvements in Type-Writing Machines, of which the following is a specification.

Our invention relates to type-writing machines, and more particularly to the carriage-stop mechanism thereof; and the object of the invention is to provide simple and efficient mechanism of the character specified.

To these and other ends, which will hereinafter appear, our invention consists in the novel features of construction, arrangements of parts, and combinations of elements to be hereinafter described, and particularly pointed out in the appended claims.

In the accompanying drawings, wherein like reference characters designate like parts in the various views, Figure 1 is a plan view of the machine with certain parts broken away and others omitted. Fig. 2 is a side view, partly in section, of the upper portion of the machine. Fig. 3 is a detail rear elevation, partly in section, of a portion of the machine, illustrating the margin-stops. Fig. 4 is an end view, partly in section, of the parts shown in Fig. 3 and looking in the direction of the arrow thereat. Fig. 5 is a detail perspective view of the stop carried by the carriage. Fig. 6 is a detail perspective view of the stop carried by the frame of the machine. Fig. 7 is a detail perspective view of the deflecting piece or cam.

While we have shown our invention embodied in a Densmore type-writing machine, it should be understood that the same may be used in other forms of writing-machines and that accordingly various changes may be made without departing from the spirit of our invention.

The main frame 1 of the machine is provided with the usual top plate 2, which con-

stitutes a portion of said frame. The top plate has upwardly-extending lugs or standards 3, that support a traverse-rail 4, which is surrounded by a sleeve 5, antifriction-balls 6 being interposed between said sleeve and the grooved tracks 7 in the traverse - rail. The sleeve 5 is connected to a carriage-truck 8, that is guided by the rollers 9 on a fixed guide-rail 10, and the carriage proper, 11, is operatively connected to move with the truck by forks 12, whereas the front carriage-rail or cross-bar 13 is supported upon antifriction-rollers 14, carried by the shift-rail 15.

The top plate 2 is provided with a short rack 16, which is secured to the top plate by suitable bolts 17 and nuts 18. The front face of the rack 16 may be provided with a scale that corresponds to the scale on the paper-carriage, as indicated in dotted lines in Fig. 3, except that the order or arrangement of the numerals is reversed—that is to say, the scale on the carriage reads from left to right, while that on the rack-bar 16 reads from right to left. To the rear of this rack 16 is arranged a rod 19, which is secured at its inner end by a screw within a socket in the top plate 2 and is supported at its outer end in a hole in the rearwardly - extending ear 20 of the right-hand standard or projection 3. Mounted upon this fixed bar or rod 19 is a U-shaped sheet-metal stop-frame 21, which has a cylindrical bearing that surrounds the bar 19, so that the frame is adapted to turn on the bar and be adjusted longitudinally thereon. This frame 21 contains between the side plates thereof a coiled spring 22, which bears at one end, 23, against a pin or rivet 24, and the opposite end, 25, of this spring bears against the rear straight edge of the top plate 2 of the machine, and the tendency of said spring is to force the frame forwardly and downwardly around the bar 19 and cause a tooth 26 upon the forward edge of the frame to engage between the teeth of the rack-bar 16, so as to hold said stop-frame in its adjusted position. The screw pin or pivot 24, hereinbefore referred to, passes through a hole in the rear

end of a margin-stop 27 and screws into a threaded hole in the frame 21. This margin-stop is limited in its upward movement by a pin 28, which is secured to the stop and abuts 5 against the top or horizontal portion of the frame 21. A spring 29 bears upon the pin 28, and thus normally maintains the pivoted margin-stop 27 in the elevated position. (Indicated in Fig. 4. It will be understood that in order 10 to adjust this margin-stop on the frame of the machine it is merely necessary to swing the frame 21 against the tension of its spring 22, and thereby release the tooth 26 from engagement with the teeth 30 on the rack 16. The 15 frame 21 may then be moved longitudinally upon the rod 19 until the stop reaches the desired position as indicated by the scale on the front side thereof. If the frame then be released, the tension of the spring 22 will force 20 the tooth 26 into locking engagement with adjacent teeth on the rack 16.

Coöperating with the margin-stop on the frame of the machine is a second margin-stop, which is carried by the carriage or its truck 8. 25 Thus the truck is provided with a short rack 31, which is secured at one end by a screw 32 and at its opposite end by a screw 33, and this rack is likewise provided with a scale that corresponds to a portion of the front platen-carriage scale and reads in the same direction as the latter scale, as indicated in dotted lines in 30 Fig. 3. A margin-stop support or frame 34 is mounted and adapted to slide upon the rack 31. This frame 34 has pivoted thereto at 35 35 a pawl 36, the nose of which is adapted to engage with the teeth of the rack 31, the pawl being normally maintained in this engagement by a spring 37, which bears at one end against the tail of the pawl and at its opposite 40 end against the frame 34 of the margin-stop, while a stud 38 on the pawl maintains the spring against lateral displacement. The frame 34 is provided with depending ears 39, between which is pivoted a stop 40, the pivot 45 of said stop being indicated at 41, and the arrangement of this stop is such that it is normally maintained in the position represented in Fig. 3 by its own weight. The stop 40 is provided at its upper edge with a flat portion 50 50 42, which is adapted to abut against a corresponding portion on the frame 34 to limit the swinging movement of the stop in one direction. The stop, however, is free to vibrate around its pivot in the direction of the arrow 55 thereon in Figs. 3 and 5, and the lower face of the stop is notched, so as to form a shoulder or abutment 43 to coöperate with the margin-stop 27 when the carriage is moved to the right. The frame 34 of the carriage margin- 60 stop is provided with laterally-projecting ears 44, which constitute bearings for one end of a carriage-release rod 45. This end of the carriage-release rod is flattened upon two sides, as indicated in Fig. 4, and projects through 65 circular perforations 46 in the projecting ears

44. A cam or deflecting piece 47 has a stem which extends between the ears 44 and is hung upon the release-rod 45, so as to turn therewith. The said cam 47 is of segmental shape or has rounded ends and normally hangs vertically. The said cam is arranged back of and adjacent to the shouldered stop 40 with one end slightly in advance of the shoulder 43 and is adapted to depress the stop or arm 27, with which said shouldered stop normally engages, 70 (when the carriage is returned to the right,) so as to permit the said stop to pass beyond the arm 27 and enable the operator to write within the margin. Ordinarily, however, said cam-piece alines with and passes through a 75 notch 48 in the arm 27 and has no depressing effect thereon; but when the rock-shaft 45 is turned by depressing the key or lever 49 in the direction of the arrow γ in Fig. 2 the cam 47 is swung rearwardly in the direction of 80 the arrow α in said figure and, acting upon the upper edge 50 of the stop 27, presses it down slightly and enough to enable the shouldered stop 40 to pass over the stop-arm, thus permitting the carriage to be moved farther 85 to the right than it could be moved but for the action of the cam. On the forward movement of the carriage the cam, which has previously been released by removing the finger from the key 49, will pass through the notch 90 48 in the stop-arm 27, and the stop 40 will swing freely around its pivot when it is brought into contact with the stop 27, and the carriage may therefore be fed from right to left without interruption by the right-hand 95 margin-stop mechanism. The well-understood purpose of this arrangement is to permit the carriage to move to the right beyond the position where it is ordinarily stopped by the margin-stops, so that, if desired, writing 100 may be done within the margin. During the ordinary operation of the machine the carriage will be moved to the right without depressing the release-key 49, and the margin-stops will then be in position to arrest the 105 carriage at the proper predetermined point. Owing to the fact that the margin-stop on the carriage and that on the frame of the machine are both adjustable, it is possible to obtain a greater number of stopping-points for the 110 carriage, and hence a wider margin than could be obtained if only one of these stops were adjustable. For example, if there be twenty notches in the rack 31 on the carriage and twenty notches in the rack 16 on the frame it 115 is possible to obtain a margin on the paper of a width equal to forty letter-spaces. Less than forty may be obtained by adjusting the stops on the carriage-rack.

It has been pointed out that the key or lever 49 and rock-shaft 45 constitute portions of the carriage-releasing means. Thus the rock-shaft 45 has rearwardly-extending arms 51 secured thereto, and secured to these arms by screws 52 is a carriage-feed rack 53, 120

125

130

which meshes with a feed-pinion 54, that is intermittently rotated at each depression of any of the finger-keys or the space-bar to afford a letter-space feed of the carriage in the usual manner. It will thus be understood that a depression of the lever 49 raises the feed-rack from engagement with the feed-pinion and releases the carriage from the escapement mechanism. This same movement 10 of the lever 49 permits the right-hand margin-stops on the carriage to pass the coöperating stop on the frame of the machine, as previously explained.

Certain of the features herein shown and 15 described constitute no part of our present invention, but are claimed in a separate application, Serial No. 92,839, filed by us on the 6th day of February, 1902, and of which the present application is a division.

20 What we claim as new, and desire to secure by Letters Patent, is—

1. In a type-writing machine, the combination of a paper-carriage, a margin-stop carried thereby, means for adjusting said stop 25 in the direction of the travel of the carriage, a second coöperating margin-stop carried by the framing of the machine, and means for adjusting said second-mentioned stop in the direction of the travel of the carriage.

30 2. In a type-writing machine, the combination of a paper-carriage, a margin-stop carried thereby, means for adjusting said stop in the direction of the travel of the carriage, a second coöperating margin-stop carried by the 35 framing of the machine, means for adjusting said second-mentioned stop in the direction of the travel of the carriage, means for normally maintaining one of said stops in the path of the other during the movement of the 40 carriage to the right and for permitting them to freely pass each other during the movement of the carriage to the left or in the direction of its feed.

3. In a type-writing machine, the combination of a paper-carriage, means for feeding said 45 carriage, a release-key for freeing the carriage from its feeding mechanism, a margin-stop on the carriage and a coöperating margin-stop on the framing of the machine, said stops being 50 normally in the path of each other to arrest the carriage when it is moved to the right, and operative connections between one of said stops and the release-key, whereby a single movement of the release-key will release the 55 carriage from its feed mechanism and will cause the stops to move freely past each other when the carriage is moved to the right.

4. In a type-writing machine, the combination of a paper-carriage, means for feeding said 60 carriage, a release-key for freeing the carriage from its feeding mechanism, a margin-stop on the carriage and a coöperating margin-stop on the framing of the machine, said stops being 65 normally in the path of each other to arrest the carriage when it is moved to the right,

operative connections between one of said stops and the release-key, whereby a single movement of release-key will release the carriage from its feed mechanism and will cause the stops to move freely past each other when 70 the carriage is moved to the right, and means which at all times permit the stops to move freely past each other in an opposite direction.

5. In a type-writing machine, the combination of a paper-carriage, means for feeding said 75 carriage, a release-key for freeing the carriage from its feeding mechanism, a margin-stop on the carriage, and a coöperating margin-stop on the framing of the machine, said stops being normally in the path of each other to 80 arrest the carriage when it is moved to the right, a deflecting-piece to the right of the stop on the carriage and which is normally out of the path of the stop on the framing of the machine, and operative connections be- 85

between the deflecting-piece and the release-key, whereby a single movement of the release-key will release the carriage from its feed mechanism and will cause the deflecting-piece to be moved to a position where it will 90 move one of said stops out of the path of the other when the carriage is moved to the right.

6. In a type-writing machine, the combination of a paper-carriage, means for feeding said 95 carriage, a release-key for freeing the carriage from its feeding mechanism, a margin-stop on the carriage, and a coöperating margin-stop on the framing of the machine, said stops being normally in the path of each other to arrest the carriage when it is moved to the 100 right, a deflecting-piece to the right of the stop on the carriage and which is normally out of the path of the stop on the framing of the machine, operative connections between the deflecting-piece and the release-key, 105 whereby a single movement of the release-key will release the carriage from its feed mechanism and will cause the deflecting-piece to be moved to a position where it will move one of said stops out of the path of the other 110 when the carriage is moved to the right, and means which at all times permit the stops to move freely past each other in an opposite direction.

7. In a type-writing machine, the combination of a paper-carriage, means for feeding said 115 carriage, a release-key for freeing the carriage from its feeding mechanism, a margin-stop which is carried by and adjustable on the carriage, and a coöperating margin-stop on the 120 framing of the machine, said stops being normally in the path of each other to arrest the carriage when it is moved to the right, a deflecting-piece to the right of the stop on the carriage and which is normally out of the 125 path of the stop on the framing of the machine and is adjustable with the carriage-stop, and operative connections between the deflecting-piece and the release-key which are operable at all times irrespective of the ad- 130

justment of the stop on the carriage, whereby a single movement of the release-key will release the carriage from its feed mechanism and will cause the deflecting-piece to be moved to a position where it will move one of said stops out of the path of the other when the carriage is moved to the right.

8. In a type-writing machine, the combination of a paper-carriage, means for feeding said carriage, a release-key for freeing the carriage from its feeding mechanism, a margin-stop on the carriage, and a coöperating margin-stop on the framing of the machine, said stops being normally in the path of each other to arrest the carriage when it is moved to the right, a deflecting-piece to the right of the stop on the carriage and which is normally out of the path of the stop on the framing of the machine, and operative connections between the deflecting-piece and the release-key to move the deflecting-piece laterally to bring the cam thereof into the path of the stop on the framing of the machine when the carriage-release key is operated.

9. In a type-writing machine, the combination of a paper-carriage, a margin-stop thereon and adjustable in the direction of the travel of the carriage, a second coöperating margin-stop on the frame of the machine and also adjustable in the direction of the travel of the carriage, a deflecting-piece adjustable with one of said stops, and hand-actuated means for moving said deflecting-piece to the operative position, to cause the other stop to be deflected to one side in order to enable the stop on the carriage to pass the stop on the frame.

10. In a type-writing machine, the combination of a paper-carriage, a margin-stop thereon, a margin-stop on the frame of the machine and normally in the path of movement of the stop on the carriage, and independent hand-actuated means on the carriage adapted to move the stop on the frame out of the path of

the stop on the carriage during a movement of the carriage to the right and so as to enable the stop on the carriage to pass by the stop on the carriage frame.

11. In a type-writing machine, the combination of a paper-carriage, a margin-stop on the carriage, a coöperating margin-stop on the framing of the machine, said stops being normally in the path of each other to arrest the carriage when it is moved to the right, a deflecting-piece to the right of the stop on the carriage and which is normally out of the path of the stop on the framing of the machine, and hand-actuated means connected to said deflecting-piece, whereby a movement of the hand-actuated means will cause the deflecting-piece to be moved to a position where it will move one of said stops out of the path of the other when the carriage is moved to the right, and means which at all times afford a free movement of the stops past each other in an opposite direction.

12. In a type-writing machine, the combination of a paper-carriage, a margin-stop on the carriage, a coöperating margin-stop on the framing of the machine, said stops being normally in the path of each other to arrest the carriage when it is moved to the right, a deflecting-piece to the right of one of said stops and which is normally out of the path of the other, and hand-actuated means connected to said deflecting-piece, whereby a movement of the hand-actuated means will cause the deflecting-piece to be moved to a position where it will move one of said stops out of the path of the other when the carriage is moved to the right, and means which at all times afford a free movement of the stops past each other in an opposite direction.
